[57] **CLAIM**

The ornamental design for a trailer rear wheel unit for improved turning and maneuverability, as shown and described.

DESCRIPTION

FIG. 1 is a front elevational view of a trailer rear wheel unit for improved turning and maneuverability showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

The cable has been broken away in the middle in FIGS. 3, 4, 5 and 6 to indicate indeterminate length.
